UNITED STATES PATENT OFFICE.

EDGAR A. STANLEY, OF YOUNGSTOWN, OHIO.

FORM FOR WALL CONSTRUCTION.

1,272,139.

Specification of Letters Patent.

Patented July 9, 1918.

Application filed June 24, 1915. Serial No. 36,122.

To all whom it may concern:

Be it known that I, EDGAR A. STANLEY, a citizen of the United States, residing at Youngstown, in the county of Mahoning and State of Ohio, have invented certain new and useful Improvements in Forms for Wall Construction, of which the following is a specification.

This invention relates in general to the subject of concrete structures, and more particularly to a novel and practical means for erecting walls and the like without the aid of external forms.

The common practice in building or erecting poured concrete walls involves the use of external wooden forms. This method is expensive, both in material and labor, and is also wasteful of material. As is well known, the wooden type of retaining structure for concrete is not only costly initially, but also after having served its purpose, since practically all of the material once used is usually damaged to such an extent in tearing the forms apart that it cannot be used again. Furthermore, in cases where it is desirable to provide walls constructed by this method with an external surface coating, it is difficult to make this coating securely adhere and unite with the main wall body. That is to say, since the wall concrete must become set before the external forms can be removed, the surface thereof becomes hardened to such a degree that it is practically impervious and impenetrable, thus preventing a homogeneous union with the finishing plastic coating applied thereto.

Accordingly, the present invention primarily contemplates the erection of concrete walls by a means which entirely dispenses with external wooden forms, thus obviating the many objectionable features incident to their employment, and entirely eliminating the expense thereof.

Another object of the invention is to provide a wall structure comprising a plastic wall body formed and sustained by retaining means of a character which permits the outside surfaces of the concrete body to be exposed so that the external finishing surface-coating may be applied thereto before the same sets, thereby securing a homogeneity and adhesion that is otherwise impossible.

A further object of the invention is to provide a wall construction in which the elements for retaining the plastic concrete ma-

terial remain a part of the finished structure, thereby utilizing a single element to perform a dual function. That is to say, the invention proposes to employ metal fabric forms in such a manner that the same will act as clog-forms to confine the main body of concrete and define its character and shape, and which, after serving this purpose, will remain in position to give added strength and reinforcement to the entire wall structure.

A still further object is to utilize the combined retaining and reinforcing elements in combination with a removable and collapsible core. This feature of the invention is of much practical importance, since it makes possible a maximum economy in both plastic material used and elements left in the wall, without sacrificing strength or rigidity. Aside from this economic aspect, the combination of the fixed retaining elements and removable core as proposed, provides a hollow wall structure which is especially desirable since it provides heat and cold insulating air spaces, is a retardant to sounds, and provides convenient means for installing pipes, wires, and the like.

A general object, including all of the foregoing special objects, is to provide for the erection of walls on a large scale involving the particular features set forth with a minimum expenditure of time and labor. In this connection, the invention proposes to utilize the removable and collapsible core devices for supporting a trackway for a concrete distributing car or the like, thus facilitating the construction to a material degree.

With the above and other objects in view which will more readily appear as the nature of the invention is better understood, the same consists in the novel construction, combination and arrangement of parts herein-after more fully described, illustrated and claimed.

In the embodiment of the invention disclosed in the accompanying drawings,

Figure 1 is a top plan view of the collapsible core devices arranged between spaced concrete retaining members, and having the covers or caps of the cores in position for supporting a trackway.

Fig. 2 is an enlarged detail plan view of one of the collapsible core devices with the cover plate in position, and also showing its connection with the metal fabric forms.

Fig. 3 is an enlarged detail plan view of one of the collapsible core devices in use, the cover plate being removed to show the interior structure thereof.

5 Fig. 4 is an enlarged fragmentary sectional view of the collapsible core device.

Fig. 5 is a detail perspective view showing the construction of the anchor ties and their connection with the metal fabric element 10 and the collapsible core.

Fig. 6 is a detail vertical sectional view of a finished wall structure showing the anchor ties, and their connection with the collapsible core before the latter has been removed from the wall.

Similar reference characters designate corresponding parts throughout the several figures of the drawings.

In carrying out the present invention, 20 which proposes to eliminate the use of external forms and otherwise facilitate and improve the erection of walls and the like, it is intended to employ open work or skeleton-like retaining elements, such as metal-fabric forms which may be of any suitable 25 character or design. However, in all cases the retaining means or metal fabric is utilized as a so-called "clog mesh", that is it is used for restraining and holding the main 30 body of concrete while at the same time permitting the latter to ooze or squeeze through the same to a sufficient extent to form a plastic base upon which the external finishing material may be applied before the 35 hardening or setting of the mass. In other words, the spaced concrete retaining elements 1 are preferably made of sheet metal and comprise an open mesh body which becomes clogged when concrete is poured between the same, thus backing up and holding 40 the body of concrete caged therebetween to permit the same to set and harden in the usual manner, as well as admitting of the desirable finishing operation referred to. 45 It will of course, be understood that meshes of various size and design may be utilized, the selection depending entirely upon the character of the work, but in the present instance, for the purpose of illustration, 50 there is shown a conventional form of wire fabric, which can be more clearly observed from Fig. 5.

In order to set up and hold these concrete retaining elements, or clog mesh forms 55 1, in proper spaced relation, the same are connected by means of anchoring elements or ties 2 with suitable supporting units preferably in the form of removable and collapsible core devices designated in their entirety by the reference letter C. These anchoring ties 2 may be of any construction 60 adapted for the purpose, but preferably are embodied in the form illustrated in the drawings, which is practical and capable of 65 producing the desired results. That is to

say, each anchoring tie may comprise a body portion 3 having one end thereof slotted to provide oppositely disposed mesh engaging fingers 4 and 5, adapted to be bent or deflected so as to respectively engage 70 both sides of the clog mesh forms and thus securely hold the same. The opposite end of the anchoring tie may be provided with outturned bracing feet 6, and an intermediate holding tongue 7. The said outturned 75 bracing feet 6 of the tie preferably bear against the outer face of one of the side wall members 8 of the collapsible core C, thus bracing the tie against a lateral swinging movement, while the intermediate holding tongue 7 temporarily enters a holding slot S formed in the side wall 8, and is bent into holding position to prevent the clog mesh from being pulled away from the core when the plastic concrete is poured between the spaced concrete retaining elements 1. It will thus be apparent, that the original set-up includes the spaced concrete retaining elements or clog mesh forms 1 which are held in position by means of 85 anchoring ties 2 connecting the same with the removable core devices C. In this connection it may be noted that the mesh engaging fingers 4 and 5 of the ties are designed to have a permanent engagement 90 with the clog mesh forms, while the holding tongue 7 has a temporary engagement with the side wall of the collapsible core device, as will hereinafter more fully appear.

Referring more particularly to the structural features and characteristics of the collapsible and removable core devices C, it will be observed more especially from Figs. 3 and 4 that each of the same is of hollow elliptical form and essentially comprises the 100 opposite side wall members 8, and the movable end cap sections 9. For the purpose of connecting the overlapping side members 8 and the end members 9, and permitting their collapse, so that the entire device may be removed from the wall after the concrete is set, there is provided a plurality of collapsible clip devices 10. These collapsible clip devices include telescoping members 11 and 12 which are respectively carried by the end 110 caps 9 and side wall members 8, and are so designed that they provide a freeway portion 13 and a contracted socket portion 14. To further increase the effectiveness of the connection between the relatively contractible and expansible members 8 and 9, the latter members 9 carry fixed guide strips 15 which slidably engage in the guide straps 16 carried by the members 8, as will be apparent from an inspection of Figs. 3 and 4. 115 120 125

For the purpose of effecting the relative movements of the members 8 and 9 to collapse the core device, and to also expand the same to its normal position, there is provided an interior operating mechanism des- 130

gnated generally as M. This mechanism essentially includes the crossed contracting levers 17 which have pivotally connected to their outer ends as at 18, a draw bar member 19, adapted to move within the limits of the collapsible clip member 10. Normally, that is when the collapsible core device is in its expanded position, these crossed contracting levers 17 assume the position 10 shown in Fig. 3, and are held in this position by means of an expanding toggle 20, connected as at 21 with a toggle operating link 22 which is pivoted as at 23 to an actuating lever 24. In connection with the normal position of these parts, it will be observed from Fig. 3 that the draw bar members 19 are within the freeway portions 13 of the collapsible clip devices 10, thus pressing against the side wall members 8 and holding the 20 same in their normal expanded positions.

With further reference to the actuating lever 24 which has a hand grip 25, and is pivoted as at 26, it will be observed that the same has attached thereto, the oppositely disposed end cap controlling links 27 which connect at their outer ends with the eyes 28 carried by the center of the end cap sections. Thus, when the actuating lever 24 is disposed transversely of the entire core device, the links 27 are forced outwardly to their limit, to hold the end sections in proper position. Accordingly, when the main actuating lever 24 occupies this transverse position as shown in Fig. 3, it will be apparent that the contracting levers 17 are in their normal position. However, when this lever 24 is moved as shown in Fig. 4, the toggle operating link 22 will break the toggle joint 20, thus drawing the contracting levers 17 together and causing the draw bars 19 to travel from the freeway portion 13 into position to slide into the contracted socket portion 14 of the clips when the links 27 draw the end sections together. Therefore, the actuation of the lever 24 not only draws the end caps 9 together to collapse the core, but also releases the pressure on the side members 8 and draws the same inward a sufficient distance to become stripped 45 or released from the concrete. It is obvious that the outline of the core may be varied by adjusting the outer or sliding members of the contracting levers or arms 17.

Before the collapsible core device can be 55 withdrawn from the concrete wall, it will of course be understood that the temporary connection between the anchoring ties 2 and the side wall members 8 must be severed. That is, when the entire structure is set up 60 as previously described, and the collapsible core is in its normal expanded position, and the holding tongues 7 will be exposed within the interior of the core, and in order to release the same from their engagement therewith, it is proposed to utilize a gang chisel

or other suitable means to sever all of the holding tongues 7 from the body of the clip, thus releasing the cores from all holding engagement with any of the anchor ties and permitting their ready removal.

With further reference to the structural features of the collapsible core device C, it will be apparent from Figs. 1 and 2, illustrating the application thereof, that any necessary number of the same may be employed and they are supplied with a cover plate 29 when in their normal position, thus effectually housing all of the collapsing mechanism within the core and preventing concrete from being spilled thereon. This cover plate 29 is preferably provided on opposite sides thereof with rail supporting sections 30 into which rails 31 may be placed, which serve as a track-way for distributing cars, and also as an effective means 75 of alining the different core sections, as clearly shown in Fig. 1. It will therefore appear that a concrete car or other concrete conveying receptacle may be wheeled along the trackway T and the contents discharged 80 at any suitable or desired place between the concrete retaining members 1.

Referring generally to the features involved in the set-up of the present invention, it will be apparent from the foregoing description, that the spaced concrete retaining or clog mesh members 1 are held in position by the anchoring ties 2 being temporarily connected by the tongues 7 with the hollow removable core devices C. These removable core devices are arranged in succession between the spaced metal fabric structures, in their normal expanded condition, with the cover plates 29 in place and the trackway T also laid. The concrete 95 conveying vehicle may then be moved along the trackway and its contents discharged into the space between the concrete retaining members 1, thus covering up the anchoring ties 2 and backing up within the 100 limits of the said members 1, in such a manner that the concrete oozes out of the mesh to a certain extent, although the main body thereof is confined. Before this main body of concrete, having portions of its 105 surface exposed through the clog mesh, is permitted to set, it is proposed to apply a surface coating 32 which entirely conceals the metal fabric form, and sets or hardens along with the main body of concrete, thus 110 forming a homogeneous external coating and wall body.

After the wall body and external surface coating 32 has set or hardened to the desired degree, and the collapsible core devices 115 or units C are to be removed, it is necessary to sever the temporary holding tongues 7 of the anchoring ties 2 as previously indicated, thus freeing the core from any positive connection with the concrete wall struc- 120 130

ture. The core units C may then be collapsed or contracted as previously described and bodily removed from the wall, leaving the anchor ties 2 embedded in the concrete.

5 With the means involved in the present method of constructing concrete walls, it will be apparent that there is absolutely no waste of material for forms, braces, or the like, the part of the structure which constitutes the form or means for shaping the concrete, being left therein for reinforcing purposes as will be readily apparent.

10 While the foregoing sets forth a preferred and practical embodiment of the invention, it will of course be understood that various changes in the form, proportion and minor details of construction may be resorted to without departing from the spirit of the invention or scope of the appended 15 claims.

20 I claim:

1. A wall forming construction comprising spaced concrete retaining elements forming permanent parts of the completed wall, 25 temporary core units arranged between said permanent elements, and ties having a releasable connection with the core units and a permanent locked connection with said permanent elements to also form parts of 30 the completed wall.

2. A wall forming construction including spaced metal fabric forms, constituting permanent parts of the completed wall, temporary collapsible core units arranged between 35 said forms, and anchoring ties having a releasable connection with the cores to permit the removal of the latter and having a permanent locked connection with the fabric forms to also constitute permanent parts of 40 the completed wall.

3. A plastic wall-forming construction comprising oppositely disposed open mesh concrete retaining elements constituting per-

manent parts of the completed wall, a supporting unit arranged between the retaining elements, and ties connecting the said unit and said retaining elements, each tie comprising a body portion having means at one end for permanently engaging the retaining elements, and means at the other end for releasably engaging the supporting unit, said ties also constituting permanent parts of the completed wall.

4. A plastic wall-forming construction comprising oppositely disposed open mesh concrete retaining elements, a supporting unit arranged between the retaining elements, and ties connecting said unit and said retaining elements, each tie comprising a body portion having means at one end for permanently engaging the retaining elements, and means at the other end for releasably engaging the supporting unit, said latter means comprising oppositely disposed 60 outturned bracing feet and an intermediate 65 holding tongue.

5. A plastic wall-forming construction comprising oppositely disposed open mesh concrete retaining elements, a supporting unit arranged between the retaining elements, and ties connecting said unit and said retaining elements; each tie comprising a body portion having means at one end for releasably engaging said supporting unit and means at the other end for permanently 70 engaging the retaining elements, said latter means consisting of a plurality of fingers adapted to be bent to respectively engage both sides of the retaining elements.

75 In testimony whereof I hereunto affix my signature in the presence of two witnesses.

EDGAR A. STANLEY.
